UNITED STATES PATENT OFFICE

MILLER PRENTICE, OF LOUISVILLE, KENTUCKY

GREASE GUN FILLER

Application filed July 15, 1929. Serial No. 378,512.

This invention relates to a grease gun filler and more particularly adapted to be used in connection with a grease gun of the portable type, handling soft grease.

5 The principal object is to provide means for filling grease guns of the portable type, which are usually mounted on wheels, without the necessity of resorting to scoops, shovels and similar tools. At the present time it is customary to roll the grease gun as close to a barrel of grease as possible and then remove the grease from the barrel by a scoop, and in turn placing the same in the grease gun. This is a very laborious under- 10 taking and requires the constant attention of an attendant. In my invention, the grease gun will be filled without resorting to a human agency except to place the grease gun in position and operate a means for control- 15 ling the filling of the grease gun. The grease used being a viscous solid presents a problem in dispensing and handling that is not present in other commodities. After experiencing great difficulty in the handling of grease 20 and laboriously filling the gun by hand which was the recognized method, it occurred to me that in spite of the viscous nature of the grease that it could be fed into a gun under its own weight aided by gravity. I 25 experimented and found my theory to be correct, provided the cross sectional area of the opening in the dispenser was large enough to overcome the surface tension of the grease.

This surface tension, of course, varied with 30 various greases, but worked efficiently where more than half of the surface area of the bottom of the container was removed. I further found that not only would the viscous solid feed out of the container, but it would 35 feed itself entirely out, so that there would be little or no waste in the container and be no necessity for plungers or other mechanical contrivances to remove the grease from the container. I did find, however, that this 40 movement was greatly facilitated by making

an opening in the top of the container in order to break the vacuum which resulted above the grease when the same moved out of the container. This movement might be compared to a glacial movement of ice where- 45 in the ice is a solid, and although the tempera- 50 ture never went above freezing, yet the ice moved, which has been demonstrated many times by the driving of surveyor's stakes in a straight line on the ice only to find later 55 that with the movement of the ice the stakes were out of line.

Another object is to provide a connection between the barrel and the grease gun which is quickly attached and at the same time prevents the loss of grease. 60

Other objects will be disclosed in the specification and drawings forming a part of this application. 65

In the drawings:

Fig. 1 is a side elevation showing the device in operative position.

Fig. 2 is an end elevation similar to Fig. 1.

Fig. 3 is a top plan of the device.

Fig. 4 is a vertical section taken on line 70 4—4 of Fig. 3.

Fig. 5 is a vertical section taken on line 5—5 of Fig. 4.

Fig. 6 is a horizontal section taken on line 75 6—6 of Fig. 4, and Fig. 7 is a perspective of the valve plate removed.

Referring to the drawings in which similar reference characters refer to similar parts throughout the several views:

Numeral 8 designates a supporting structure, on which is placed a barrel of grease 9. Beneath the barrel of grease 9 is placed a grease gun 10. The grease gun 10 is supported by a platform 11, which in turn has rollers or wheels 12. A funnel 13 is secured to the barrel 9, by means of bolts 14, openings 15 being formed in a flange 16 around the edge of the funnel 13, so as to coincide with holes in the barrel 9 from which the cover plate has been removed. The neck portion 90

18 of the funnel 13 has a slide valve housing 19, in which is mounted a cut-off slide valve 20. The slide valve 20 has a stop member 21 which limits the opening of the valve 20 and 5 is removable so as to permit the withdrawing of the slide valve 20 for repacking purposes. The outer end has a turned up flange 22, which may be used as a hand hold for facilitating the operation of the valve 20. Below 10 the slide valve housing 19 is formed a collar 23, having an inner wall 24. Between the collar 23 and the inner wall 24, is placed a packing 25. At the top of the inner wall 24 is formed a semi-circular flange 26 in the 15 form of a lip to form a rest and valve seat for the valve 20. On the inside of the funnel 13 adjacent the slide valve housing 19 are packing holders 27, containing packing 28, the packing 28 contacting with the slide valve 20. The collar 23 and the inner wall 24 are 20 designed to fit over a rib 29 formed on the top of the grease gun 10.

The rib 29 has an annular bead 30 which acts as a stop and support for the collar 23.

25 As actually operated, the barrel of grease 9 is placed upon the supporting structure 8 and the cover plate removed therefrom. The funnel 13 is then bolted in place and the barrel 9 turned so that the funnel will be 30 directed downwardly. The grease gun 10 is then rolled into place beneath the funnel 13, the barrel being raised slightly to permit this operation. The rib 29 fits between the collar 23 and the inner wall 24. The top of the 35 grease gun 10 has previously been removed.

The operator grasps the turned up flange 22, pulling outwardly and thus operates the cut-off slide valve 20 and opens the funnel 13 so that the grease from the barrel 9 may flow 40 into the grease gun 10. Upon the grease gun being filled, the operator will push inwardly on the turned up flange 22 and thus close the cut-off valve 20. The grease gun 10 will then be removed and rolled away to the 45 desired point of use or left in position and grease dispensed beneath the barrel.

By the use of my grease filler, no grease is lost and I have found the same to be a great time and labor saver over the old methods of 50 filling grease guns. By using packing in the manner shown in connection with my structure, I find that practically no grease is lost and further that there is very little wear and tear on the apparatus.

55 Obviously, I do not intend to limit myself to the specific structure shown and described herein, but include other structures which may fall within the scope and breadth of my invention.

60 What I claim as new and novel is:

Grease dispensing apparatus comprising supporting framework, a container for slightly fluid material inverted on said framework, a dispensing funnel detachably connected to the lower end of said container and

depending below the upper part of said framework, a collar depending from the lower end of said funnel and adapted to extend into the neck of a receptacle, a semi-circular supporting flange extending into the funnel at the intersection of said collar and funnel, said funnel being slotted on the side opposite to said flange and above said flange, and a valve plate slidable through said slot into and out of supported contact with said flange.

In testimony whereof I affix my signature.
MILLER PRENTICE.
